US00D871466S

(12) **United States Design Patent** (10) Patent No.: **US D871,466 S**
Okada et al. (45) Date of Patent: **** Dec. 31, 2019**

(54) **ROTARY TOOL FOR BOAT OF SEMICONDUCTOR MANUFACTURING APPARATUS**

(71) Applicant: **Hitachi Kokusai Electric Inc.**, Toyama (JP)

(72) Inventors: **Hiromi Okada**, Toyama (JP); **Yoshikazu Takashima**, Toyama (JP)

(73) Assignee: **KOKUSAI ELECTRIC CORPORATION**, Tokyo (JP)

(**) Term: **15 Years**

(21) Appl. No.: **29/633,932**

(22) Filed: **Jan. 17, 2018**

(30) **Foreign Application Priority Data**

Jul. 25, 2017 (JP) 2017-016039

(57) **CLAIM**

The ornamental design for a rotary tool for boat of semiconductor manufacturing apparatus, as shown and described.

DESCRIPTION

FIG. 1 is a front, top and right side perspective view of a rotary tool for boat of semiconductor manufacturing apparatus showing our new design;

FIG. 2 is a rear, bottom and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

1 Claim, 4 Drawing Sheets
